No. 37,482.

Patented July 11, 1905.

UNITED STATES PATENT OFFICE.

EDWARD C. HURLBERT, OF ST. JOHNS, OREGON.

DESIGN FOR A CONDIMENTS-HOLDER.

SPECIFICATION forming part of Design No. 37,482, dated July 11, 1905.

Application filed February 18, 1905. Serial No. 246,340. Term of patent 14 years.

To all whom it may concern:

Be it known that I, EDWARD C. HURLBERT, a citizen of the United States, residing at St. Johns, in the county of Multnomah and State of Oregon, have invented a new, original, and ornamental Design for a Condiment-Holder, as shown in the accompanying drawing, which is a perspective view of the holder.

I claim—

The ornamental design for a condiment-holder, as shown.

EDWARD C. HURLBERT.
